UNITED STATES PATENT OFFICE.

HARRY EHLIG, OF PEARL RIVER, NEW YORK, ASSIGNOR TO GEORGE R. SWART & COMPANY, INC., OF NEW YORK, N. Y., A CORPORATION OF NEW YORK.

SHEET FEEDER.

Original application filed May 29, 1923, Serial No. 642,189, and in Canada June 17, 1924. Divided and this application filed February 25, 1925. Serial No. 11,418.

My invention relates to improvements in sheet feeders for automatically separating and advancing successive sheets of paper or other impression-receiving material to 5 printing, folding or ruling machines, or to such other types of machines as are devised to operate thereafter on such sheets. My present application for patent is a division of my pending application, Serial Number 10 642,189, filed May 29, 1923.

The objects of my invention are, among other things, mainly to provide a sheet-feeder of this character having a simplified design which will have embodied therein 15 separate mechanisms capable of performing efficient work, while they are not likely to get out of order, yet are very sensitive in action, all being incorporated in a feeder which will invariably separate and continuously feed or advance the successive sheets, preferably from a fanned-out bank of paper on the feed-board, both automatically 20 and with great rapidity.

With this aim in view I have devised a 25 front-edge feeder which will separate and advance the successive sheets by mechanism or devices operating on the front edges or margins of the stacked-up sheets, the sheet forwarding mechanisms for the bank of 30 sheets being controlled by the steady and continuous advance of the front margins of the pile or bank of paper supported on the feed-board beneath the feeding-off devices.

A further feature of my invention is to 35 embody in the feeder a novel and improved form of suction feeding-off device which is usually arranged in pairs across the feeder for successively separating and feeding the sheets forwardly, the operation of each set 40 being controlled by a separate cut-out or trip finger located between the usual feed rolls which finger not only limits the forward movement of the particular suction feeding-off device but also cuts off the suction 45 from such device at a predetermined point to release the advancing sheet. Each suction device operates independently of the other so as to straighten the leading edge of the advanced sheet as it is seized by the 50 feed-rolls.

Another feature is to provide a novel and simplified pile detector mechanism which operates in conjunction with means for smoothing out the front margins of the suc-

cessive sheets as they are fed forwardly, 55 which will also operate independently of the suction feeding-off devices, and also independently of the number or timing of the sheets advanced thereby, so as to inaugurate and control the action of the bank 60 feed or pile feed mechanism by which the sheets of paper may be advanced and maintained at the proper thickness beneath the suction feeding-off devices operating on the front margins of the sheets, all through the 65 continued operation of the sheet-feeder itself.

My improved sheet-feeder also embodies other advantageous features of novelty and improvement in which the different operating parts are greatly simplified in form, arrangement and interaction, and are made more effective and otherwise better adapted 70 for use, all of which will be hereinafter described and then particularly pointed out 75 in the appended claims.

The accompanying drawings show my improvements in their preferred embodiment in a continuous sheet-feeder; such improvements, however, are not to be restricted to 80 any particular type of sheet-feeder, as these features of invention may be embodied in various forms of feeders with similar advantages and results.

Of the drawings, Fig. 1 is a side elevation looking from the left in Fig. 2, certain parts being omitted;

Fig. 2 is a front elevation of the feeder with the central parts broken away;

Fig. 3 is a sectional view taken on the 90 line 3—3 of Fig. 2 looking in the direction of the arrow; and

Fig. 4 is a sectional view taken on the line 4—4 of Fig. 2 looking in the direction of the arrows.

Similar numerals refer to similar parts throughout the several figures.

Referring more particularly to Figs. 1-4, the two side-frames 7 and 8 of the feeder proper are supported upon the standards 9 and 10, respectively; between the side-frames 7 and 8 and suitably secured thereto is the lower feed-board 11 over which travel a series of feed belts 12 to advance the fanned-out bank of sheets 13 along the feed-board 11. The belts 12 (two being shown in Fig. 2) pass around the drum 14 mounted on the transverse shaft 15 journalled in

suitable bearings in the frames 7 and 8. The shaft 15 carries the ratchet 16 by which the feed-belts 12 are intermittently advanced over the feed-board 11 to carry the bank of fanned-out sheets 13 to the sheet separating and feeding-off devices arranged across the front edge of the feed-board 11.

In the present embodiment of my feeder, the sheet separating and advancing devices are duplicated upon either side of the machine, and a description of one set of such devices will therefore suffice, as both sets are built and operate alike. Referring more particularly to Figs. 2, 3 and 4, the carriage plate 17 is adjustably secured to the tie-shaft 18 by the split-collar 19 and clamping bolt 20 so that the carriage 17 may be transversely shifted in the feeder to accommodate sheets of different widths. The upper bracket 21 of the carriage 17 carries the collar 22 within which is journalled the main cam-shaft 23 which extends across the feeder and is suitably supported in bearings in the side-frames 7 and 8 as shown in Fig. 2. This shaft 23 has secured thereto the gear 24 which engages the pinion 25 mounted on the stub-shaft 26 journalled in the side-frame 7, the shaft 26 also carrying the gear 27 enmeshing with the idler gear 28 which is driven by the pinion 29 fast to the main power shaft 30 which is suitably journalled in the side-frames 7 and 8, the arrows shown in Fig. 3 indicating the respective directions of revolution of the several gears to rotate the cam-shaft 23 in a clockwise direction.

Extending across the feeder and suitably journalled in the side-frames 7 and 8 is the rock-shaft 31 to which is slidably secured the sleeve 32 by the key 33 to rock with the shaft 31. Loosely secured on one end of the sleeve 32 and rotatably mounted in the carriage 17 is the oscillating suction feed-sector 34, and surrounding the sleeve 32 is the coil spring 35, one end of which is fastened to the collar 36 pinned to the sleeve 32 and the other end is fixed to the pin 37 on the feed-sector 34 as shown in Fig. 2. The tension of the spring 35 normally forces the sector 34 forwardly. The segmental rim 38 of the feed-sector 34 carries the spaced-apart perforations 39 preferably arranged in staggered relation as shown in Fig. 2; the suction mouth-piece 40 with its nozzle 41 bears on the inner face of the perforated rim 38, and is held in position by the hollow arm 42 attached to the transverse suction tube 43 secured in the side-frames 7 and 8. The nozzle 41 is arranged to register intermittently with the successive perforations 39 in the feed-sector 34 as the latter swings forwardly. The required suction to operate the feed-sector 34 is applied to the tube 43 by any suitable air-exhausting means not shown. The sheets from the bank 13 adhere to the

exterior surface of the rim 38 opposite the nozzle 41 as shown in Fig. 3, and are separated and advanced to the bite of the lower feed-rolls 44 and coacting upper feed-rolls 45.

The feed-rolls 44 are rotatably mounted on the shaft 30, while the feed-rolls 45 are secured to the cross-shaft 46 journalled on the arms 47 of the bell-crank lever 48 pivotally mounted to the cross shaft 49 journalled in the side-frames 7 and 8; the upper arm 50 of the lever 48 carries the cam-roller 51 which rides on the cam 52 mounted on the cam-shaft 23. The coil spring 53 pinned to the arm 47 and to the side frame 7 causes the upper feed rolls 45 to contact with the driven lower feed-rolls 44 in timed relation to seize the leading edge of the sheet when the cam-roller 51 enters the drop of the cam 52, the arrangement shown in Fig. 3 showing the roll 45 in raised position with the cam roller 51 riding on the dwell of the cam 52.

The rock-shaft 31 is intermittently oscillated forwardly to rock the sleeve 32 and release the feed-sector 34 held under tension of the spring 35 to advance the adhering sheet in proximity to the bite of the feed-rolls 44 and 45 by the following described mechanism: The shaft 31 carries the arm 54 connected by the link 55 with the arm 56 of the bell-crank lever 57 rotatably mounted on the shaft 15. Pivotaly connected to the lever 57 is the link 58 carrying on its end the cam-roller 59 to engage the cam 60 fixed to the cam-shaft 23. The link 58 is formed with the intermediate slot 61 through which passes the shaft 23 to support link 58 and the shaft 23, and permit its movement by the cam 60. Secured to the lever 57 is the arm 62 which is normally forced upwardly by the compression spring 63 (Figs. 2 and 3) to hold the cam-roller 59 in engagement with the cam 60 fixed to the cam-shaft 23. The relative positions of the cams 52 and 60 are such that as the sector 34 is ending its forward stroke the feed roll 45 is lowered into contact with the feed-roll 44 to seize the leading edge of the sheet which has been separated and fed forwardly by the sector 34.

Means are provided to arrest the forward stroke of the feed-sector 34 and likewise to shut off the suction from the nozzle 41 immediately upon the seizure of the sheet by the feed-rolls 44 and 45, which mechanism may be widely varied in structure and operation. In the present embodiment the lower bracket 64 of the carriage 17 carries the screw-pin 65 which in turn supports the

cut-out or trip finger 66, the forward end being forked with the tips 67 riding in parallel grooves 68 formed in the underlying feed-roll 44 as shown in Figs. 2 and 4. The finger 66 is screwed to the supporting plate 69 carried by the collar 70 pivotally mounted on the pin 65 as shown in Figs. 3 and 4; projecting rearwardly from the collar 70 is the latch-arm 71 with its triangular-shaped tip 72 held adjustably by the light spring 73 in engagement with the lower arm 74 of the pawl 75 pivoted on the hub 76 fast in the bracket 64. The coil-spring 77 secured to the arm 74 and the carriage 17 normally pulls the arm 74, when released from the latch-arm 71, to the right in Fig. 3 to lift the pawl 75 into engagement with the segmental rack 78 affixed by screws to the feed-sector 34. By this mechanism the forward swing of the feed-sector is arrested and immediately ceases when the advanced sheet through the trip finger 66 releases the pawl 75 to engage the teeth of the rack 78, while the rock-shaft 31 and sleeve 32 complete the forward oscillation as the cam-roller 59 follows the drop in the cam 60, and the finger 66 is slightly raised from the sheet.

Referring to Figs. 2, 3 and 4, the sleeve 32 carries at one end the curved rock-arm 79 projecting downwardly and forwardly from the shaft 31, and also the rock-arm 80 extending rearwardly as shown particularly in Fig. 3. The arm 79 carries the lug 81 on the outside and adjustably supports the screw-threaded stop-pin 82 which engages with the projection 83 carried by the hub 76. When this arm 79 is rocked in an anti-clockwise direction as the cam-roller 59 rides out of the drop of the cam 60, the pawl 75 is thereby disengaged from the rack 78, and the arm 74 is swung forwardly over the tip 72 of the latch-arm 71 against the tension of spring 77 to reset the latch-arm 71 as shown in Fig. 3.

The mechanism to shut off the suction from mouthpiece 40 after the forward movement of the feed-sector 34 is arrested by the engagement of the pawl 75 with the rack 78 in the present embodiment is best shown in Figs. 2, 3 and 4. The inner side of the mouth-piece 40 has cut therein the port 84 which is opened and closed by the swinging valve plate 85 integral with the sleeve 86 pivotally mounted on the screw-pin 87 secured to the bracket 88 formed on the top of the mouth-piece 40 as shown in Fig. 2. Secured to the sleeve 86 are the arms 89 and 90, the arm 89 devised to contact with the adjustable screw-pin 92 threaded in the bracket 91 mounted on the rock-arm 79, while the arm 90 is arranged to coact with the adjustable screw-pin 93 threaded in the end of the rock-arm 80. When the forward movement of the feed-

sector 34 is arrested by the pawl 75, the pin 93 is so adjusted as to engage the arm 90 to swing the valve-plate 85 which opens the port 84 to atmosphere and cuts off the suction from the mouthpiece 40 and nozzle 41 and releases the sheet adhering to the rim 38. In like manner the port 84 is closed by the valve 85 and suction pressure again maintained in the mouth-piece 40 when the rock-arm 79 is oscillated in a clockwise direction so that the pin 91 engages the arm 89 to swing the valve 85 into its closing position. The positions of the pins 91 and 93 are so adjusted with relation to the arms 89 and 90, that the port 84 is opened slightly after the arrest of the forward movement of the feed-sector 34 by the pawl 75 engaging the rack 78, and the port 84 is closed when the sector 34 is being retracted as the sleeve 32 is oscillated as the roller 59 rides out of the drop of the cam 60. By these mechanisms the release of the advanced sheet from the feed-sector 34 is synchronized with the arrest of its forward movement by the pawl 75 restricting the swing of the feed-sector 34, the operation of this mechanism being controlled by the releasing of the latch members 71 and 72 when the leading edge of the advanced sheet raises the trip finger 66, all during the continued operation of the feeder.

The front edges of the sheets comprising the bank 13 are kept separated by a blast of air from the nozzle 94 mounted on the pipe 95 connected with any suitable air pump not shown; the sheets then pass over the guide plates 96 (Figs. 3 and 4) mounted on the tie rod 97, the plates 96 having curved extensions 98 upon which the front margins of the sheets rest (Fig. 3) at the forward end of the feed-board 11.

The detector mechanism which controls and inaugurates the action of the bank feed independently of the successive feeding movements of the oscillating feed-sector 34 in advancing the sheets from the bank 13 is best shown in Figs. 2 and 4. Such mechanism comprises the detector finger 99 suitably mounted in the sleeve bracket 100 pivoted to the pin 101 secured to the end of the rock-lever 102 mounted on the stub-shaft 103 affixed to the side-frame 8 (Fig. 4). The arm 104 of the lever 102 carries the cam-roller 105 held in engagement with the cam 106 on the cam-shaft 23 by the expansion spring 105^a coiled about the rod 105^b pinned to lever 102. When the roller 105 rides on the dwell of the cam 106 in the position shown in Fig. 4, the finger 99 is retracted with its tip raised slightly above the top sheet by the hub 100 engaging the rounded projection 107 of the forked rock-shoe 108 pivoted on the shaft 109 secured to the side-frame 8 (Fig. 2); when the cam-roller 105

falls into the drop of the cam 106, the finger 99 is moved forwardly over the top surface of the sheets, and the rock-shoe is lowered on the front margins to smooth out as well 5 as to hold the front margins of the sheets lightly in position, since the adjustable screw-pin 110 threaded in the lug 111 integral with the shoe 108 follows the lever arm 102 until such lug 111 engages the stop-pin 10 112. In like manner the backward swing of the arm 102 when the roller 105 rides out of the drop of the cam 106 raises the shoe 108 to the position shown in Fig. 4, while lifting 15 the tip of the finger 99 slightly above the top sheet on the bank.

As shown in Fig. 4, the guide plate 96 is formed with an intermediate slot 113 through which projects the vertical arm 114 of the latch-lever 115 pivoted to the stub shaft 116 secured to the side-frame 8 (Fig. 2). The upper face 117 of the arm is flat and inclined forwardly in the plane of the guide-plate 96 with the notch 118 centrally cut therein in alinement with the detector 99, 20 as shown in Figs. 2 and 4. Also as shown in Fig. 4, this notch 118 is normally covered by the leading edges of the top sheets of the bank 13 (in the embodiment shown in Fig. 4 by two sheets) which prevent the finger 99 from entering the notch 118. The arm 114 is returned to its vertical position (Fig. 4) by the force of the spring 119 coiled about 25 the rod 120 pinned to the arm 114, the outer end of the rod 120 passing slidably through the bracket 121 secured to the frame 8, the spring 119 being held under compression by the threaded collar 122 screwed on the rod 120. Secured to the shaft 116 is the laterally-extending latch-arm 123, having the 30 shoulder 124 cut therein to engage with the triangularly-shaped block 125 pinned to the end of the lower arm 126 of the bell crank lever 127 rotatably mounted on the shaft 15. The short arm 128 carries the spring pressed 35 pawl 129 which coacts with the ratchet 16 fast on the shaft 15, while the longer arm 130 of the lever 127 carries the cam-roller 131 to engage the cam 132 secured to the shaft 23. Depending from the pin 133 on 40 the arm 130 is the rod 134 which slides through a hole in the bracket 135 secured to the frame 8; between the bracket 135 and the collar 136 adjustably secured to the rod 134 is the expansion spring 137 coiled about the rod 134. Fig. 4 shows the position of the 45 pawl 129 when the cam-roller 131 is riding upon the dwell of the cam 132 with the spring 137 under compression. When the sheets in the bank 13 become depleted so 50 that the front edges of the top sheets fail to cover the notch 118, the detector finger 99 enters and engages this notch on its forward stroke and thereby swings the arm 114 to the left which releases the latch arm 123 55 from the block 125; this release of the latch-

ing members allows the arm 126 to swing to the left when the cam-roller 131 arrives at the drop of the cam 132 through the force of the spring 137. This rocking movement of the bell crank lever 127 in a clockwise direction retracts the pawl 129 over several teeth of the ratchet 16, and when the cam-roller 131 rides out of the drop of the cam 132, the ratchet 16 is rotated in an anti-clockwise direction to advance the feed-belts 75 12 to forward the bank of sheets until the top sheets thereof again cover the notch 118, and the arm 114 impelled by the spring 119 resumes its vertical (Fig. 4) position to reset the shoulder 124 of the latch-arm 123 80 into engagement with the block 125 as shown in Fig. 4. The timing of the cams 106 and 132 is such that detector finger 99 has completed its forward stroke to release this latch-arm 123 just before the drop in the 85 cam 132 is reached when the cam-roller 131 is free thereafter to fall into such drop preparatory to the forward feed of the bank 13.

The operation of my sheet-feeder is substantially as follows: When the pair of feed-sectors 34 have picked up the top sheet from the bank 13 as shown in Fig. 3, they swing forwardly in unison with the sheet under the impulse of the coil springs 35 released from compression when the cam-roller 59 falls into the drop of the cam 60 and the rock-shaft 31 is oscillated in a clockwise direction. Whenever the leading edge of the advanced sheets lifts either one of the trip fingers 66 in position to be seized by the bite of the feed rolls 44 and 45, the latch-arm 71 is drawn down to release the pawl arm 74 which allows the pawl 75 to engage the rack 78 to immediately arrest the forward stroke of the particular feed-sector 34 which has been tripped, although the sleeve 32 and shaft 31 complete their predetermined oscillations under the influence of the cam 60. By this mechanism the separate trip fingers directly control the 100 length of the forward feed of each feed-sector 34, and the leading edge of the sheet is thereby straightened, if required, when placed in position at the bite of the feed 105 rolls 44 and 45. 110

As soon as the forward movements of the separate feed-sectors 34 have been arrested by the pawl 75 and rack 78 engagement, the rotation of the sleeve 32 causes the arm 90 to contact with the stop-pin 93 to shift valve 85 to the left (Fig. 3) to open the port 84 thereby also opening the mouth-piece 40 and nozzle 41 to atmosphere which releases the hold of the feed-sectors 34 on the sheet now in position to be seized by the feed rolls 44 and 45. When the cam-roller 59 rides out of the drop of the cam 60, the rock-shaft 31 and sleeve 32 are rocked to restore the feed-sectors 34 to their feeding 120 position while the springs 35 are again put 125 130

- under compression for the next forward stroke: during this retractive movement the arm 89 engages with the stop-pin 91 to shift the valve 85 to the right (Fig. 3) to close 5 the port 84 and place the mouthpiece 40 again under suction in readiness for the feed-sectors to take up the next sheet in the succeeding cycle of operation. During this movement each trip-finger latch resets itself 10 by the arm 74 passing over the tip 72 of the latch-arm as hereinbefore described, and the trip finger 66 will again lower and rest in the grooves 68 as shown in Fig. 3 in readiness for the next advancing sheet. The 15 timing of the cams 53 and 60 is such that the feed roll 44 will lower as the sheet reaches the feed-roll 45 in the forward feed of the sectors 34.
- When the feed-sectors 34 have separated 20 and advanced the top sheets from the bank 13 to diminish the thickness thereof so that it becomes desirable or necessary to advance the pile or bank of sheets by moving the feed-belts 12 on the feed-board 11, the detector finger 99 in its forward stroke engages the exposed notch 118 cut in the face of the arm 114 so as to swing the arm 114 forwardly and release the latch arm 123 from engagement with the block 125, where- 25 by the bell-crank lever 127 is rocked in a clockwise direction. This allows the cam-roller 131 to enter the drop of the cam 132 when the latter has rotated sufficiently, and in that part of the cycle the pawl 129 is 30 simultaneously drawn backwardly over the teeth of the ratchet 16. When the bell-crank lever 127 is rocked in an anti-clockwise direction by the roller 131 riding out of the drop of the cam 132, the ratchet 16 rigidly 35 secured to the shaft 15 will advance the feed-belts to forward the bank of sheets. Such bank-feed movement through this pawl and ratchet mechanism will be repeated with each revolution of the cam 132 40 until the front margins of the top sheets have been advanced to cover the notch 118 so that the detector finger 99 no longer can swing the arm 114 forwardly in each cycle; the spring 119 straightens the arm 114 which enables the latch-arm 123 to reset 45 itself with the block 125 as has been heretofore described. So long as this latch is set the spring 137 is held under compression 50 with the cam-roller 131 riding only on the dwell of the cam 132 and bridging the drop therein. Such detector control and bank-feed mechanism is very delicate and sensitive in action with the coacting rock-shoe 55 108 serving to smooth out the front edges of the sheets as they are advanced to the feed-rolls during each forward movement of the detector finger 99 over the front edges of the sheets.
- The foregoing constructions embody the 60 essential principles of my invention as em- bodied in a continuous sheet-feeder, but various changes may be made in the structural details without departing from the scope of my improvements. However the foregoing is sufficient to disclose the underlying principles and advantages of my invention as particularly applied to a continuous sheet- 65 feeder.
- I claim as my invention:—
1. In a sheet-feeder, a feed-board, means for advancing a pile or bank of sheets along said feed-board, means comprising a part normally reciprocated along the front margins of the sheets in each cycle for inaugurating the action of said advancing means when said part falls below said front margins of the sheets, and means for smoothing out the front margins of the sheets elevated therefrom when said part is retracted. 70
  2. In a sheet-feeder, a feed-board, means for advancing a pile or bank of sheets along said feed-board, means comprising a part normally reciprocating along the front margins of the sheets in each cycle for inaugurating the action of said advancing means when said part falls below said front margins of the sheets, and means controlled and actuated by said advancing means for smoothing out the margins of the sheets. 80
  3. In a sheet-feeder, a feed-board, means for advancing a pile or bank of sheets along said feed-board, means comprising a part normally reciprocated along the front margins of the sheets in each cycle for inaugurating the action of said advancing means when said part falls below said front margins of the sheets, and means lowerable in conjunction with the forward movement of said part for smoothing out the margins of the sheets. 85
  4. In a sheet-feeder, a feed-board, means for advancing a pile or bank of sheets along said feed-board, means comprising a part normally reciprocated along the front margins of the sheets in each cycle for inaugurating the action of said advancing means when said part falls below said front margins of the sheets, and means for smoothing out the margins of the sheets in each cycle of operation, said means being elevated from the sheets during the retraction of said part. 90
  5. In a sheet-feeder, a feed-board, means for advancing a pile or bank of sheets along said feed-board, means comprising a part normally reciprocated along the front margins of the sheets in each cycle for inaugurating the action of said advancing means when said part falls below said front margins of the sheets, and means controlled and actuated by said advancing means for smoothing out the margins of the sheets in each cycle of operation. 95
  6. In a sheet-feeder, a feed-board, means for advancing a pile or bank of sheets along 100

- said feed-board, means comprising a part normally reciprocated along the front margins of the sheets in each cycle for inaugurating the action of said advancing means when said part falls below said front margins of the sheets, and means lowerable in conjunction with the forward movement of said part for smoothing out the margins of the sheets in each cycle of operation.
7. In a sheet-feeder, normally inoperative sheet-advancing means, a detector normally reciprocated along the front margins of the sheets to control the action of said sheet-advancing means, and a rock-member to smooth out the margins of the sheets when
- 5 said detector falls below said margins, and elevated with said detector when the latter is retracted beyond said front margins.
8. In a sheet-feeder, normally inoperative sheet-advancing means, a detector normally reciprocated in an elliptical path along the front margins of the sheets to control the action of said sheet-advancing means, and a vertically movable rock-member to smooth out the margins of the sheets when said detector in its forward movement falls below said margins, and elevated with said detector when the latter is raised and retracted beyond said front margins. 20 25

HARRY EHLIG.
